L. F. ROSE.
MULTICOPY ATTACHMENT FOR TYPEWRITERS.
FILED JUNE 20, 1921.

INVENTOR.
Leonard F. Rose
By Carlton L. Sibley
ATTY.

UNITED STATES PATENT OFFICE.

LEONARD F. ROSE, OF SAN FRANCISCO, CALIFORNIA, ASSIGNEE, BY DIRECT AND
MESNE ASSIGNMENTS, TO NETOGRAPH COMPANY, INC., A CORPORATION OF CALI-
FORNIA.

MULTICOPY ATTACHMENT FOR TYPEWRITERS.

Application filed June 20, 1921. Serial No. 478,937.

To all whom it may concern:

Be it known that I, LEONARD F. ROSE, a citizen of the United States, residing in the city and county of San Francisco and State of California, have invented a new and useful Improvement in a Multicopy Attachment for Typewriters, of which the following is a specification.

My invention relates to improvements in multi-copy attachments for typewriters wherein a plurality of slotted members or bars having typewriter ribbons mounted in said slots operate in conjunction with means for maintaining said members between sheets of paper upon a platen of a typewriter and opposite the point of contact of the type-bars with said platen to produce a plurality of copies all of which have the appearance of being originals.

20 The primary object of the present invention is to provide a new and improved multi-copy attachment for typewriters.

Another object of the invention is to provide a new and improved device of the character described which is arranged to produce a plurality of ribbon instead of carbon copies.

30 A further object is to provide improved means for producing copies of typewritten matter which shall be simple, cheap and effective in operation and construction and having a maximum efficiency.

A still further object of the invention is to provide improved means for eliminating the use of carbon sheets in producing copies of typewritten matter, thereby effecting a saving of time, labor and expense and simultaneously providing a plurality of copies of neater and sharper appearance.

40 I accomplish these and other objects by means of the device disclosed in the drawings forming a part of the present specification wherein like characters of reference are used to designate similar parts throughout the said specification and drawings, and in which:

Fig. 1 is a transverse sectional view of a portion of the carriage of a typewriter disclosing my improved attachment applied thereto;

Fig. 2 is a broken front elevation, partly in section, of Fig. 1;

Fig. 3 is an enlarged broken elevation of a portion of one of the slotted members disclosing the ribbon mounted in said slot: 55

Fig. 4 is a still further enlarged broken transverse sectional view of the front portion of the platen and portions of a plurality of sheets of paper thereon disclosing the arrangement of my multi-copying device; and 60

Fig. 5 is a broken sectional view disclosing the manner in which all of the members may be removed from between the sheets simultaneously. 65

Referring to the drawings the numeral 1 is used to designate in general the carriage of a typewriter having the usual platen 2 mounted thereupon, and 3 a number of sheets of paper wound upon said platen 2. 70

Plates 4 are secured to the side members of the carriage 1 and are provided with lugs 6 within which is mounted a suitable rod 7. Upon the rod 7 a plurality of arms 8 are arranged in pairs each pair being rigidly 75 connected by means of nested sleeves 9 so that when either arm of a pair is raised or lowered, the opposite arm of the same pair will be raised and lowered simultaneously. 80

Detachably connected, in any suitable manner, between the free ends of each pair of arms is a slotted member 11 within the slot of which is mounted, under a slight tension, a typewriter ribbon 12, said ribbon 85 being slightly thinner than said bar and having the back thereof arranged flush with the back of said bar so as to normally prevent contact of said ribbon 12 with the front or writing surface of the adjacent sheet of 90 paper 3.

In order to prevent contact of the back surface of the ribbon 12 in one slotted bar 11 with the back of the sheet 3 in front of said bar 11, I have covered the said back 95 of said bar 11 with a resilient or fibrous shield 14 which may be of any light texture, such as a sheet or strip of stencil paper which is designed and adapted to withstand blows from a type bar and therefore is admirably suited for this purpose. The shield 14 covers the slot and the ribbon 12 therein so that the rear surface of the sheet 3 immediately in front of the bar 11 will be pre- 100

- vented from contacting with said ribbon when the platen 2 is rotated to turn the sheets upwardly a space of one or two lines during the process of typewriting.
- 5 In order to facilitate the placing and removal of the slotted members 11 between their respective sheets 3 I have provided outwardly extending tabs formed integrally with the arms 8, the tab 16 of the inner 10 pair of arms 8 extending under and beyond the other arms 8 beyond it so that when it is desired to remove all of the members 11 the same may be easily and readily accomplished by raising the said tab in which 15 case said tab will engage the under sides or edges of the remaining arms 8 and raise all of the said arms and their respective ribbons 12 away from the platen and to an inoperative position as disclosed in dotted 20 lines in Fig. 1 of the drawings.

To normally retain the arms 8 in an operative or inoperative position I have provided the resilient spring member 17 which is arranged to engage one flat edge of 25 the squared ends of the arms 8 and by exerting a pressure thereunto normally retain said arms in either an operative or inoperative position.

In operation the members 11 with their 30 respective ribbons 12 are placed one between each sheet of paper 3 rolled upon the platen 2, as disclosed in Fig. 4 of the drawings.

This will bring the slot of the member 11 and the ribbon 12 therein directly opposite 35 the point of contact of the type bar 18 with the platen 2 so that when said type bar 18 is operated said bar 18 will contact with the regular ribbon 19 which is carried by the typewriter and make an impression on the 40 front of the first or top sheet of paper 3 on the platen 2. The force of the impact of said type bar 18 will cause the intervening ribbons 12 to be carried onto the front surfaces of their respective sheets 3 and im- 45 press an impression of the type bar 18 thereon thereby producing multi-copies with ribbon impressions instead of carbon impressions.

In this manner every copy will be a ribbon 50 copy or what is known as an original for the reason that said copies will bear ribbon instead of carbon paper impressions.

The saving of time, labor and expensive carbon paper is very obvious. Not only 55 will the cost of the carbon paper be eliminated but also the time and labor of inserting a sheet of carbon paper between every two sheets of paper will be saved.

The use of this invention will also facilitate 60 erasing or correction of copies and effect a saving of time in such erasures or corrections. Where carbon sheets are used it is necessary to first move the paper up one or two lines to render the error accessible for 65 erasure.

The sheets of paper and carbon must next be separated separately and a rigid shield must be placed in back of the sheet to be erased to prevent the pressure, created by erasing, from causing an impression to be 70 made from the next carbon underneath. This operation must be repeated for every sheet of paper on the platen 2.

Where the present invention is used it is only necessary to rotate the platen 2 in the 75 usual manner to render the error accessible for erasure after which each sheet may be easily corrected without inserting a protective shield behind the sheet being erased.

With this invention it should also be noted 80 that it is not necessary to insert and align sheets of carbon paper with the sheets to be written before inserting into the machine. It is only necessary to feed the required number of sheets onto the platen and 85 then move the first or innermost slotted bar 11 in front of the last sheet of paper or that sheet next to the platen. Then place the next sheet of paper 3 over this strip or bar 11 and place the next or successive bar 11 90 in front of the second sheet of paper 3, and repeat this operation until the required number of sheets have been placed. The usual ribbon operated by the typewriter will make the first sheet or impression and the slotted 95 bars 11 with their respective ribbons 12 will produce the copies.

While I have illustrated only three slotted members 11 with their respective ribbons 12 it is obvious that a larger number of bars 100 may be used. The thickness of the bars 11 is only slightly greater than the thickness of the ribbon 12 mounted within the slot so that the entire ribbon and member 11 form 105 a very thin sheet and therefore a great number of copies may be produced as the total thickness of all of the bars 11 plus the thickness of the total number of sheets of paper is very small.

Having thus described my invention what 110 I claim as new and desire to secure by Letters Patent is:

1. An attachment for typewriters comprising a plurality of slotted members; typewriter ribbons suspended in said slots; means for normally retaining said slotted members and ribbons between sheets of paper on the platen of said typewriter and at a point opposite the point of contact of the type bars of said typewriter with said 115 platen.

2. An attachment for typewriters comprising a plurality of slotted members; typewriter ribbons suspended in said slots; means for normally retaining said slotted 125 members and ribbon between sheets of paper on the platen of said typewriter and at a point opposite the point of contact of the type bars of said typewriter with said platen; and means for preventing contact of the 130

backs of said ribbons with the back surfaces of adjacent sheets.

3. An attachment for typewriters comprising a plurality of slotted members; typewriter ribbons suspended in said slots; means for normally retaining said slotted members and ribbons between sheets of paper on the platen of said typewriter and at a point opposite the point of contact of the type bars of said typewriter with said platen; means for preventing contact of the backs of said ribbons with the back surfaces of adjacent sheets; and means for removing all of said members and ribbons simultaneously.

4. An attachment for typewriters comprising a plurality of slotted bars arranged to be inserted between sheets of paper upon the platen of a typewriter and opposite the point of contact of the type bars of said typewriter with said platen; typewriter ribbons mounted in said slots and arranged flush with the back surface of said bars; and a shield mounted upon the back of each bar and covering the slot and ribbon therein to prevent contact of the back of said ribbon with the back surface of the adjacent sheet of paper.

5. An attachment for typewriters comprising a plurality of slotted bars arranged to be inserted between sheets of paper upon the platen of a typewriter and opposite the point of contact of the type bars of said typewriter with said platen; typewriter ribbons mounted in said slots and arranged flush with the back surface of said bars; and a shield mounted upon the back of each bar and covering the slot and ribbon therein to prevent contact of the back of said ribbon with the back surface of the adjacent sheet of paper; and means for removing all of said bars from between the sheets of paper simultaneously.

6. An attachment for typewriters comprising a plurality of slotted bars pivotally mounted upon a typewriter carriage and arranged to be moved between sheets of paper upon the platen of said typewriter and opposite the point of contact of the type bars of said typewriter with said platen; typewriter ribbons mounted within each slot and flush with the back surface of the member to normally prevent contact of said ribbon with the front surface of an adjacent sheet; and a flexible shield mounted upon the back surface of each bar and covering the slot and ribbon therein to prevent contact of said ribbon with the back of an adjacent sheet of paper.

7. An attachment for typewriters comprising a rod mounted upon the carriage of a typewriter; a plurality of arms pivotally mounted in pairs upon said rod; means rigidly connecting each pair of arms; a slotted bar detachably connected between the free

ends of each pair of arms, each bar arranged to be held by its respective pair of arms between sheets of paper upon the platen of said typewriter and opposite the point of contact of the type bars of said typewriter with said platen; a ribbon mounted within each slot and arranged flush with the back surface of the member to normally prevent contact of said ribbon with the front surface of an adjacent sheet of paper; and a shield mounted upon the back of each slotted bar and covering the slot and the ribbon therein to prevent contact of said ribbon with the back surface of an adjacent sheet on that side of said bar.

8. An attachment for typewriters comprising a rod mounted upon the carriage of a typewriter; a plurality of arms pivotally mounted in pairs upon said rod; means rigidly connecting each pair of arms; a slotted bar detachably connected between the free ends of each pair of arms, each bar arranged to be held by its respective pair of arms between sheets of paper upon the platen of said typewriter and opposite the point of contact of the type bars of said typewriter with said platen; a ribbon mounted within each slot and arranged flush with the back surface of the member to normally prevent contact of said ribbon with the front surface of an adjacent sheet of paper; a shield mounted upon the back of each slotted bar and covering the slot and the ribbon therein to prevent contact of said ribbon with the back surface of an adjacent sheet on that side of said bar; and means for raising all of said arms and bars simultaneously to remove said slotted bars and ribbons from between said sheets of paper.

9. An attachment for typewriters comprising a rod mounted upon the carriage of a typewriter; a plurality of arms pivotally mounted in pairs upon said rod; means rigidly connecting each pair of arms; a slotted bar detachably connected between the free ends of each pair of arms, each bar arranged to be held by its respective pair of arms between sheets of paper upon the platen of said typewriter and opposite the point of contact of the type bars of said typewriter with said platen; a ribbon mounted within each slot and arranged flush with the back surface of the member to normally prevent contact of said ribbon with the front surface of an adjacent sheet of paper; a shield mounted upon the back of each slotted bar and covering the slot and the ribbons therein to prevent contact of said ribbon with the back surface of an adjacent sheet on that side of said bar; and means for normally retaining said slotted bars either opposite or away from said point of contact.

In witness whereof I hereunto set my signature.

LEONARD F. ROSE.
